UNITED STATES PATENT OFFICE.

SIDNEY C. SLADDEN, OF FREEPORT, NEW YORK.

FIREMAN'S WATER-SCREEN APPARATUS.

Application filed December 2, 1924. Serial No. 753,457.

Among the principal objects which the present invention has in view are: To form a sheet of water between a fire and fire fighters to prevent the passage of heat therethrough; to produce a sheet of flowing liquid between a fire and firemen for absorbing the heat rays emitted by the fire; to form a continuously flowing sheet of heat absorbing liquid between a fire and the fighters thereof; to provide means for delivering water or fire-reducing liquid from a position above the fire, the liquid being delivered in an approximately horizontal sheet; to deliver fire-reducing liquid between adjacent walls not accessible to fire fighters or for the implements at present employed; and to produce the screen herein disclosed in the most efficient or heat absorbing condition.

20

Drawings.

Figure 1 is a side view of an apparatus constructed and arranged in accordance with the present invention, the same being shown as attached in service to a fireman's hose nozzle of usual construction, the nozzle and a portion of the apparatus being shown in section to expose the interior construction thereof.

30 Figure 2 is a longitudinal section of the apparatus, the section being taken as on the line 2-2 in Figure 1.

Figure 3 is a top plan view of a fireman's hose and nozzle equipped with a water screen apparatus and shown in conjunction with a supporting stand or table.

Figure 4 is a side view of the same.

Description.

40 As seen in the drawings, the herein disclosed apparatus is adapted to be operatively connected with a fireman's hose nozzle of usual construction and indicated in the drawing by the numeral 9. To this end an externally threaded collar 10 is mounted on the nozzle 9, the threads of the collar being adapted to engage the internal threads on a coupling 11. The coupling 11 is rotatively connected with the water screen apparatus 50 and with the neck 12 thereof. The neck 12 rotates within the collar 11 and for this purpose has mounted at the inner end thereof a bearing ring 13 which forms a race for bearing balls 14. It will be noted that the complete races for the balls 14 are formed by

the ring 13 and a washer 17 held against an inturned flange 15 on the collar 11.

It will be noted that the pressure exerted by the column of water in the screen apparatus forces the ring 13 upon the balls 14, 60 and the balls 14 upon the washer 17 seated against the flange 15 of the coupling 11. Any frictional drag on the screen apparatus is thereby avoided except as in so far as the balls 14 produce.

65 The flanges 15 and 16 as seen best in Figure 1 of the drawings operate to maintain the relative position of the screen apparatus and the nozzle 9 and parts associated therewith.

70 Two elements in the apparatus cooperate to rotate the same on its axis. Within the neck of the apparatus are formed internally extended inclined vanes 18. The vanes 18 are inclined to the travelling column of 75 water so as to produce a rotation of the apparatus in the direction indicated by the arrow A, in Figure 1, or contra-clockwise. The rotary impulse imparted by the vanes 18 is augmented by the laterally opening 80 passages 19 formed in the head 20 of the apparatus. The borings of the passages 19 are somewhat tangential so that water being delivered from the head 20 is delivered at an inclination to the radii of the head 20. 85 The streams of water thus delivered press upon the air with the result that the head 20 rotates upon its axis.

85 As seen best in Figure 2 of the drawings, the head 20 is provided with an inverted 90 cone 21, the side of which is curved to form a deflecting surface leading to the various passages 19. The cone 21 is preferably constructed of solid metal, as seen in Figure 2, the weight of which is utilized to steady the 95 rotary action of the head. It will be understood, however, that should it be desired, the cone may have a hollow center or chamber.

100 With an apparatus constructed and arranged as described, it will be seen that if water under pressure is delivered through the nozzle 9 into the apparatus, it will press primarily upon the vanes 18 and upon the inclined surface thereof to impart a side 105 pressure thereon which is translated into rotation of the apparatus. The water passing through the neck 12 is deflected by the cone 21 to the passages 19 through which the water escapes to the outer air in a number of 110

separated streams, each leaving the cone at a slightly tangential direction or direction slightly inclined from the radii of the head 20. The forces thus exerted result in the 5 rapid rotation of the head 20, which action has an effect on the streams delivered from the passages 19 to seemingly bend the same backward from the direction of the rotation of the head, an action which results in the 10 more positive mixing of the sprayed columns of water delivered by the passages 19.

It will be noted that in Figure 2 of the drawings the passages 19 are also inclined for delivery of the water slightly toward 15 what may be termed the direction in which the nozzle 9 is pointed. This results in delivering the screen forward from the head 20 and from the firemen or operators who are in attendance upon the apparatus and 20 the nozzle 9 connected therewith.

It is obvious that when in operation the spray of various streams delivered from the head 20, mingle to form a substantial sheet of water radiating from the head 20. Heat 25 rays delivered thereon are absorbed thereby. The water continuously moving outward results in carrying off in a way the heat thus absorbed. In other words, the direct result of the operation is to form a screen through 30 which the heat of the fire does not penetrate so that firemen locating behind the screen can approach in closer proximity to the heated area than before.

In Figures 3 and 4 of the drawings is 35 shown a supporting table 22 upon which the nozzle 9 may be held by clamps 23, or other suitable devices. Locking latches 24 may be employed to hold the clamps 23 in service. The table 22 is preferably provided with 40 legs 25. These are held in service position by the braces 26. In Figures 3 and 4, the nozzle 9 is shown as connected to a hose pipe 27 of suitable construction.

It will be understood that while I have 45 described the action of the apparatus as forming a water screen, it may be used in various other ways such as, by inserting the nozzle equipped with the apparatus through a hole in any floor of a building when the 50 water may be delivered in a horizontal sheet to all parts of the lower apartment and in a

wide spread manner, and therefore more effective manner, than when delivered by means of a single stream. This is peculiarly advantageous in fighting a fire in a cellar. 55 Further, the nozzle may be extended through an opening in a side wall and the spray be effective on said side wall, not otherwise accessible. This use is of advantage where a fire is inside the walls of a partition as the 60 water would be delivered above and below inside the partition walls. It will also be observed that firemen might utilize the apparatus as a heat or smoke screen for protecting firemen from the heat and smoke of an 65 overhead structure. The streams of water have the effect upon smoke of creating a draft which carries the smoke in lines parallel with the streams emitted from the passages 19 and thereby creates a clear and 70 smokeless space back of the screen.

While I have herein disclosed the apparatus as having a pointed cone 21 by means of which the total output of water passing through the head 20 is delivered through 75 the passageways 18, it will be understood I may have a central opening through the cone 21 which delivers a stream directly in front of the said head, thereby operating in the two-fold capacity of a screen, and a stream delivering nozzle. I prefer, however, the use of the apparatus for forming a screen behind which firemen are at liberty to work delivering through the screen, other streams of water for fire fighting purposes. 85

Claim.

In a nozzle, a distributor head having a neck integral therewith and arranged for connection to a source of water supply, inclined vanes disposed in said neck for imparting rotation to said neck and head on passage of water therethrough, an inwardly extending central conoidal deflector carried by the end of said head and extending into 95 said neck, said head having a plurality of delivery openings annularly arranged about and flush with the base of said deflector to deliver water streams substantially at right angles to the stream passed through said neck. 100
